FIG. 1 is a front view of an electronic copying machine display screen with transitional graphical user interface showing our new design in a first display state; and, FIG. 2 is a front view thereof in a second display state, the graphical user interface transitioning from the first display state to the second display state.

(51) **LOC (10) Cl.** 14-04

The appearance of the transitional image sequentially transitions between the images shown in FIGS. 1 and 2. The process or period in which one image transitions to another forms no part of the claimed design.

(52) **U.S. Cl.**

The dash dot dash line showing the display screen forms no part of the claimed design. The broken line showing of the remainder of the graphical user interface and the electronic copying machine forms no part of the claimed design.
